UNITED STATES PATENT OFFICE.

WILLIAM E. LAWRENCE, OF MINERSVILLE, PENNSYLVANIA.

TOOTH-BRUSH HOLDER.

No. 835,732.

Specification of Letters Patent.

Patented Nov. 13, 1906.

Application filed October 24, 1905. Serial No. 284,187.

To all whom it may concern:

Be it known that I, WILLIAM E. LAWRENCE, a citizen of the United States, residing at Minersville, in the county of Schuylkill and State of Pennsylvania, have invented certain new and useful Improvements in Tooth-Brush Holders, of which the following is a full, clear, and exact description.

My invention is designed for the production 10 of an improved tooth-brush holder, the primary object of which is to provide a device of this kind upon which tooth-brushes of varying sizes may be supported in such a manner that the bristle or active portion of 15 the brush is completely protected from dust, water, and other foreign particles, while at the same time it is in free communication with the air, so that it may readily dry out after it has been used.

20 The invention consists of a support or back plate and a housing secured thereto within which the brush is inserted and held, the upper end of said housing being closed and the lower end open.

25 It also consists of a support or back plate, a tube secured thereto, into which the brush is adapted to be inserted, the upper end of said tube being closed and the lower end open, and a spring in said tube for retaining the 30 brush in place.

It also consists in certain features and details of construction and combination of parts, which will be hereinafter more fully described and claimed.

35 In the drawings forming part of the specification, Figure 1 is an elevation of a tooth-brush holder embodying my invention and showing a tooth-brush in place therein. Fig. 2 is a vertical section of the same with the 40 brush removed. Fig. 3 is a sectional view on the line 3-3 of Fig. 2, and Fig. 4 is a detail perspective view of the spring employed.

Like reference-numerals indicate like parts in the different views.

45 In the form of my invention herein shown, 1 represents a back plate or support, provided with openings 2 near its upper and lower ends, respectively, through which screws or other form of securing devices may 50 be passed for attaching the same to a wall or other fixture. Secured to the front side of the plate 1 is a housing 3 for the tooth-brush. This has been shown in the form of a glass tube having its upper end closed and its 55 lower end open and which when the device as a whole is in place is vertically disposed.

The said tube is removably connected to the back plate 1, so that it may be readily disconnected at any time for the purpose of cleaning it. A convenient means of mounting the tube or housing 3 upon the back plate 1 is illustrated in the drawings, although I do not wish to be limited thereto, as it is obvious that different means of connection may be substituted for that shown. The means 60 illustrated comprises a metal cap 4, which fits over the upper end of the tube 3 and has a loop 5 formed in its side flange, which extends through an opening in the plate 1 and through which a securing-pin 6 passes. A 70 ring 7 embraces the lower end of the tube 3 and is secured to the plate 1 in the same manner that the cap 4 is secured thereto. The said ring 7 is provided with an annular flange 8 around its lower edge, upon which the tube 75 rests and is supported when the parts of the device are assembled.

Coöoperating with the parts above enumerated is a spring 9, which is located within the tube 3 and serves to hold the brush in place 80 when the latter is inserted into the tube. Any suitable form of spring may be employed; but I prefer to use a spring of the form illustrated in the drawings, which consists of a wire secured at its ends to a disk 10 and bent so 85 as to form two parallel arms 11 11 and a connecting-piece 12 at the lower ends of said arms. The disk 10 fits and is secured within the cap 4, the same being located between the upper end of the tube 3 and the top or 90 cover portion of said cap. The spring 9 extends down into the tube 3 and preferably projects below its lower end.

Constructed as above described, it will be seen that in order to support a tooth-brush it 95 is merely necessary to insert the head or bristle end of the brush into the lower end of the tube or housing 3, when the same will be acted upon by the spring 9 and be prevented from accidental removal. When in place, 100 the brush is completely housed and protected from dust, water, and other foreign substances, while at the same time, by reason of the fact that the lower end of the tube 3 is open, the bristles are enabled to dry out by 105 being in free communication with the atmosphere. By reason of the peculiar shape of the spring 9 it will be seen that no matter in what position the brush may be inserted into the tube 3 it will still be acted upon by said 110 spring and be prevented from accidental removal.

I have illustrated and described but one tube or housing as being mounted upon the back plate 1. It is obvious, however, that any number of said tubes may be secured to said back plate by merely increasing the dimensions of said plate. The device may thus be made so that it is capable of supporting any number of brushes at the same time.

To remove the tube 3 for the purpose of cleaning it, it is merely necessary to disconnect the pin by means of which the ring 7 is secured to the plate 1, when said ring and said tube may both be detached from their support. Reassembling of the parts will of course call for a mere reversal of this operation.

While the spring 9 or some equivalent thereof is desirable in order to adapt the device for holding tooth-brushes of different sizes, it will be obvious that such spring may in some instances be dispensed with and the brush supported in some suitable manner—as, for instance, by the frictional contact between the bristles thereof and the inner surface of the tube 3. In such case, however, it would be necessary that a comparatively close fit be obtained between the tube 3 and the brush which it is to receive.

The upper end of the tube or housing 3 has been described as "closed." This term has been used in a relative sense, however, as it is obvious that the cap 4 need not be completely closed.

Having described my invention, I claim—

35 1. A tooth-brush holder comprising a support, and a tube secured thereto, the lower end of the tube being open for the reception of the brush, and the tube being supported independently of the brush.

40 2. A tooth-brush holder comprising a support, a tube secured thereto, for the reception of the brush, and a spring for retaining the brush in said tube, the latter being supported independently of the brush.

45 3. A tooth-brush holder comprising a supporting-plate, a tube removably secured thereto for the reception of the brush, and a cap for the upper end of said tube.

50 4. A tooth-brush holder comprising a supporting-plate, a tube removably secured

thereto for the reception of the brush, a cap for the upper end of said tube, and a spring within said tube for retaining the brush in place.

5. A tooth-brush holder comprising a supporting-plate, a vertically-disposed tube on the front of said plate for the reception of the brush, a cap covering said tube and secured to said plate, and a ring embracing the lower end of said tube and removably connected to said plate, the said ring having an annular flange on which said tube is supported.

6. A tooth-brush holder comprising a supporting-plate, a vertically-disposed tube on the front of said plate for the reception of the brush, a cap covering said tube and secured to said plate, a ring embracing the lower end of said tube and removably connected to said plate, the said ring having an annular flange on which said tube is supported, and a spring for retaining the brush in place in said tube.

7. A tooth-brush holder comprising a supporting-plate, a vertically-disposed tube on the front of said plate for the reception of the brush, a cap covering said tube and secured to said plate, a ring embracing the lower end of said tube and removably connected to said plate, the said ring having an annular flange on which said tube is supported, and a spring extending down into said tube for retaining the brush in place.

8. A tooth-brush holder comprising a supporting-plate, a vertically-disposed tube on the front of said plate for the reception of the brush, a cap covering said tube and secured to said plate, a ring embracing the lower end of said tube and removably connected to said plate, the said ring having an annular flange on which said tube is supported, a disk secured within said cap and a spring for retaining the brush in place secured to said disk, the said spring having two parallel arms and a connecting-piece between said arms at their lower ends.

In witness whereof I subscribe my signature in the presence of two witnesses.

WILLIAM E. LAWRENCE.
